UNITED STATES PATENT OFFICE.

ERNST W. BRACKELSBERG, OF HAGEN, WESTPHALIA, PRUSSIA, GERMANY.

TYPE SETTING AND DISTRIBUTING APPARATUS.

SPECIFICATION forming part of Letters Patent No. 253,153, dated January 31, 1882.

Application filed July 12, 1881. (No model.) Patented in England April 16, 1881, in France April 16, 1881, in Germany April 17, 1881, in Belgium April 19, 1881, in Austria-Hungary June 24, 1881, and in Italy June 30, 1881.

To all whom it may concern:

Be it known that I, ERNST WILHELM BRACKELSBERG, resident in Hagen, Westphalia, Kingdom of Prussia, Germany, have invented a new and useful Improved Type Setting and Distributing Apparatus, (for which Letters Patent have been applied for in Germany, Great Britain, and France on the 16th of April, 1881, and in Belgium on the 19th of April, 1881,) of which the following is a specification.

This invention relates to a type-setting and type-distributing apparatus of a simpler and therefore more reliable arrangement than those hitherto executed. The same is represented on the annexed four sheets of drawings.

Figure 1 is a side view in which the front plates of the different guides are supposed to have been taken off for the purpose of showing more distinctly the parts which they cover. The stationary part of the apparatus is in section. Fig. 2 is a projection of the apparatus on a plane parallel to the inclined type-case, partly in section. Fig. 3 is a side view of the type setting or composing mechanism, with portion of a type-channel. The movable parts are in this figure in a position different from Fig. 1. Fig. 4 is a horizontal section of the composing mechanism on line 3 4, Fig. 3; Fig. 5, a front view, and Fig. 6 a back view, of the same mechanism, with movable parts corresponding in position to Fig. 1. Fig. 7 is a vertical section on line 5 6, Fig. 3, with a front view of the type-channels, the plate *c* of which is removed. Fig. 8 is a section on line 12, Fig. 3. Figs. 9 and 10 are side views of the type-distributing mechanism, the movable parts being represented in positions differing from each other and from their position in Fig. 1. As in the latter figure, all front plates of the guides have been left away in these figures and in Fig. 3. Their place is, however, shown by the holes for the screws by which they are to be fastened. Fig. 11 is a section on line 9 10, Fig. 9. Fig. 12 is a section on line 11 12, Fig. 10. Fig. 13 is a front view, and Fig. 14 a back view, of the distributing mechanism, the movable parts being in the same position as in Fig. 1. Fig. 15 is a section on line 7 8, Fig. 9. Fig. 16 is a section on line 13 14, Fig. 9. Fig. 17 is a view of the holding-down bar *w'*. Figs. 18 and 19 are side views of a

modified arrangement of a portion of the distributor. 50

The apparatus comprises three main parts—first, the type case *D*, Fig. 2, fixed in an inclined position on the table or frame *A*; secondly, the setting or composing mechanism *B*, 55 (henceforth to be called the "composer,") and, thirdly, the distributing mechanism or distributor *C*.

The type-case *D* consists of a number of parallel channels or grooves, *b*, each containing a single row of types of the same denomination. 60 On account of the inclination given to the type-case the types have a tendency to slide downward in the channels *b*. The front type of each row is thus pressed by the superincumbent types and by a follower, *j*, against the plate *c*, which closes the channels *b* in front. The bottom of each channel has an aperture, *i*, at its front or lower end corresponding in size to the thickness of the type. (See Figs. 1 and 7.) 65 The said apertures may be formed by notches cut into a ledge, *f*, which can be exchanged for another such ledge having notches of different depth. This arrangement allows the apparatus to be employed for setting types of different width, as the only alteration required in such case is to make the depth of the apertures *i* correspond to the width of the types. 70 Across the top of the front end of the type-channels a loose bar, *k*, is placed, which serves 75 to hold down the types. Between this bar and the projecting edge of the plate or wall *c* there is a narrow slit.

The setting mechanism or composer *B* is a device which is movable on guides at a right angle to and in front of the type-channels, so that it may be brought opposite to any one of these channels for the purpose of ejecting a type into the composing-race which is fixed to it. The said mechanism consists, in the first place, of an ejector-bar, *t*, suitably guided in a direction parallel to the types contained in the type-case, and drawn upward by a spring, *u*. At its lower end, and in a line with the front type of any row, the bar *t* carries the tongue or ejector *l*, by which the types are pushed downward into the composing-race *r*. 80 The types dropping into this race are prevented 85 from falling out by a stop *s* which is held in position by a spring *v*. The bar *t* is guided in a slot *g* in the frame *A*. The slot *g* is inclined at an angle of 90° to the horizontal, so that the bar *t* is 90 inclined at an angle of 45° to the type-channels. The slot *g* is closed at the top by a cover *h*, which is held in place by a screw *z*. The cover *h* has a slot *h'* 95 through which the bar *t* passes. The cover *h* is inclined at an angle of 45° to the horizontal, so that the bar *t* is inclined at an angle of 45° to the type-channels.

from falling on their side by means of a slide-rest, l' , provided with a spring, which, by pressing against the side wall of the race, causes a certain frictional resistance. Any type transferred into the composing-race is pushed forward, together with those transferred previously, by means of the type-driver x , projecting into the race from the rear. This type-driver is actuated by the rod t by means of its inclined surface c' , and of the lever a' , whose lower end engages in a notch cut into the arm e' , fixed to the driver, and sliding in a suitable guide. (See Fig. 4.)

f' is a spring, which, by acting on the arm e' , draws the driver into the composing-race, and which consequently also presses the top end of the lever a' against the bar t . The spring f' may be omitted in case the bar t is provided, for instance, with a slit of suitable form, in which a pin engages which is fixed to the lever. For moving the driver in the required manner by the bar t other arrangements might, however, also be employed.

The rear part, y , of the type-driver serves, in co-operation with the vertical grooves m arranged beneath the type-channels, for correcting the position of the composer—*i. e.*, for exactly shifting it into its place after this has been done approximatively by hand. For the said purpose the rear end of the part y , which is to be called the "adjuster," is chamfered on both sides, as are also the projecting ledges between the grooves m . Instead of the grooves holes widened out conically at the front end might also be employed, in which case the adjuster would have to consist of a pointed pin fitting into the said holes.

The composer is fixed on a bar, p , guided between two ledges, n , or in other suitable manner, and provided with a knob, k' , and a pointer, q . Opposite to the course of the latter there is a register, o , of the types contained in the channels b , and the arrangement is so made that when the pointer q is on the center of any letter or other character of the register the composing-race r will be exactly below the one of the channels b which contains the types corresponding to such letter or character. At the same time the ejector l is exactly above the front type within the said channel.

The operation of this part of the apparatus is as follows: The slide-rest l' in the composing-race having been pushed close to the driver x , the composer B is so shifted by hand and by aid of the knob k' that its pointer q is brought on, or nearly on, the line indicating the center of the letter, &c., having the denomination of the type to be set. The ejector-bar is then depressed and allowed to ascend again. The type is thereby transferred into the composing-race r . When the bar t begins to descend its inclined surface c' acts on the lever a' , which consequently pushes the driver x backward, whereby a space for a type is produced in the race r . Simultaneously the adjuster y at the rear end of the type-driver en-

ters into the groove m which is opposite to it at the time being, and, supposing the true position of the composer not to have been fully attained by hand, the adjuster, when entering into the groove, shifts the composer precisely into its proper place, so that the top end of the composing-race r is brought exactly under the channel b which contains the required type. The adjuster having completely entered into the groove m keeps the composer locked during the remaining part of the operation. The bar t descending farther, the ejector l fixed to t enters into the slit between the front wall, c , of the type case and the holding-down bar k , and thereupon pushes the front type from the channel b into the composing-race r . The wall c and the bar k are beveled at their opposite upper edges, so that the ejector may easily enter into the slit between the same. At the point where the type drops into the composing-race the edges of the side walls of the latter are also beveled. It may yet be observed that the bar k only rests by its weight (to which the tension of a spring may be added) on the type-channels, so that it can give way toward the rear in case the ejector should press against it. The ejector-bar t having been released, the spring u draws it upward, together with the ejector. During this motion of the latter the type which is now in front of the row, and which is pressed against the ejector, is prevented from being drawn along by the same by means of the bar k . During the latter part of the ascending motion of the bar t the driver x acts by the force of the spring f' on the type which has been deposited and pushes it forward, together with the slide-rest l' , by a distance equal to its thickness. At the same time the adjuster y recedes from the groove m , so that the composer may be shifted again. The ejector having left the channel b , the row of types contained therein, and which is impelled by its own weight and by the weight of the follower j , slides forward on the inclined bottom of the channel and again presses the front type against the wall c . The relative effect of the follower j increases as the number of types in the row becomes smaller.

For the purpose of making the drawings more comprehensible the bar t has been represented as being provided with a knob at its upper end. It is, however, the intention of the inventor to depress this bar by means of another bar arranged above the former and parallel to the guides n , and to which a vertical reciprocating motion is to be imparted, either by hand or by means of a treadle.

By the successive adjustments of the composer according to the letters of the manuscript, and by the repeated depression of the ejector-bar, the required types are deposited in the composing-race in a line, which is thereupon removed by hand and united with the lines composed previously.

The distributing of types is effected by the distributer C , in co-operation with certain ar-

rangements at the upper or rear end of the type-case. (See Figs. 1, 2, and 9 to 17.)

To the upper end of the type-channels *b* a cross-bar, *m'*, is fixed, provided with notches, 5 which correspond in position with the channels *b*, and in size with the types contained therein. This bar may be exchanged for another one having notches of different depth when types of other thickness are to be distributed. In 10 each type-channel there is a slide-rest, *l'*, similar to the one described with regard to the composing-race *r*, and which, by its friction against the walls of the channel, keeps the type in upright position and prevents them from 15 sliding. These slide-rests reach with their end nearly to the bar *m'*, when they are pushed with their shoulder against the bar *o'*. Near the upper edge of the frame A are arranged the guides *p'*, between or on which the distributor slides. *q'* is a register of the different 20 types, which corresponds in the same manner with the channels *b* as the register *o*.

The distributor comprises principally the distributing-race *t'*, for the reception of the line or 25 lines to be decomposed, and the mechanism which, after having corrected the position of the distributor, transfers the front type from the race *t'* into the corresponding type-channel *b*. The distributor is fixed to a bar, *r'*, provided at its other end with a pointer, *s'*, which 30 is in the same relation to the distributing-race *t'* as the pointer *q* is to the composing-race—that is to say, when the pointer *s'* is adjusted on a certain character of the register *q'* the race *t'* 35 is in a plane with the one of the channels *b* which contains the types corresponding in denomination with the said character. The distributing-race, however, travels with its fore end above the type-channels, while the composing-race projects under them.

The operating parts of the distributor comprise, in the first place, the ejector-bar *u'*, the holding-down bar *w'*, and the bar *x'*, by which motion is imparted to the other movable parts. 45 These three bars are placed by the side of each other in a common guide, (see Fig. 15,) and they move in a direction parallel to the types. The bar *x'* is drawn upward by a spring, *z'*. To the lower end of the bar *u'* the ejector *u* is 50 so fixed that it is in a line with the front type contained in the distributing-race *t'*. The said bar *u'* is connected with the bar *x'* by the spring *b'*, which tends to draw *u'* downward relatively to *x'*; but the action of this spring is limited 55 by the contact of the projection *z'* of the bar *u'* with the projection *a'* of the bar *x'*. In a similar manner the bar *w'* is connected with the bar *x'* by the spring *e'*, which draws the former downward in respect to *x'*, the motion 60 being in this case limited by a pin, *d'*, screwed into bar *u'*, and by the length of the slit *c'* cut into the bar *w'*, the said pin projecting into this slit. Other equivalent arrangements for limiting the motion of the bars *u'* and *w'* may, 65 however, be employed.

In the lower part of the distributor the bar

*m*² is placed, which serves as adjuster for correcting the position of the distributor, and also as driver for the types transferred into the channels *b*. When the bar *x'* is depressed the 70 said bar *m*² is moved forward in two steps by the two inclined surfaces *i'* and *k'*, provided for on the back of the bar *x'*, and by the medium of the lever *f'*, which engages with its lower end in a notch cut into a lateral projection of 75 the bar *m*². (See Figs. 9, 10, 11, 12, and 16.) The bar *x'* being released, the spring *z'* draws it upward, while the spring *o* returns the bar *m*² and the lever *f'* into their normal position.

The distributing-race is closed in front by 80 the part *v'*, carrying a transverse piece, *r'*, serving to close the front of the notch *n'* of the bar *m'*, through which a type is to be pushed.

The bottom of the distributing-race is open 85 at the front end, and the types are here supported by the aforesaid bar *m'*, which thus forms a continuation of the bottom of *t'*. One or more lines to be distributed having been put into the race *t'*, the follower *v'* is inserted, 90 which, being impelled forward by the spring *w'*, presses the types against the front wall, *v'*, of the race. Instead of this spring-follower a weight might, however, be employed, as in the type-channels *b*. The slide-rests *l'* in the channels *b* are then all pushed with their shoulder 95 against the bar *o'*, whereby they are brought in the position proper for supporting the first type transferred from the distributing-race into any channel *b*. Hereupon the apparatus is so shifted that the pointer *s'* points approximately 100 on the center of the letter of the register *q'* which corresponds with the first type to be deposited, and finally the bar *x'* is depressed and released again. The effect hereof is as follows: During the first period of the downward motion of *x'* the inclined surface *i'*, acting on the lever *f'*, causes the bar *m*² to be shifted forward and to enter into the corresponding type-channel. The fore end of the bar and the rear end of the partition-walls between 110 the channels *b* being beveled on both sides, (see Fig. 11,) the described motion produces a correction of the position of the distributor in every case in which it has not been adjusted accurately by hand. After the correction the 115 race *t'* will consequently be truly above the channel *b*. (See Fig. 9 with position of *x'* in dotted lines, and Fig. 11.) The bars *u'* and *w'* descend in the first period by as much as *x'*. During the second period of the motion the 120 straight surface *j'* of the bar *x'* slides along the end of the lever *f'*. The lever and the bar *m*² will consequently remain at rest. The two bars *u'* and *w'*, however, descend farther with the bar *x'*. The holding-down bar is pressed 125 by the tension of the spring *e'* with its projection *d'*, Fig. 17, against the top of the walls of the race *t'*, so that its foot *c'* does not touch the types. The bar *u'*, on the other hand, causes the ejector *u* fixed thereto to press against the 130 type which is below the same, and to push it by the tension of the spring *b'* through the

notch n' into the type-channel b . (See Figs. 9 and 11.) The bar u' finally strikes against the foot c^3 of the bar w' , whereby its motion is stopped. In the third period the bar x' completes its downward course against the strain of the springs e^2 and b^2 , (which are forced to expand on account of the stoppage of u^2 and w^2 ,) and in acting by its inclined surface k^2 , and by the medium of the lever f^2 on the bar m^2 , it pushes the same farther into the channel b . The bar m^2 for its part drives the deposited type and the slide-rest l' forward by the thickness of the type, for the purpose of producing the necessary space for the following type. (See Figs. 10 and 12.) The bar m^2 thus moves forward in two steps having an interval between them, in which the type is transferred from the channel b to the race t' . The stroke of the bar x' is limited by a screw, b^3 , striking against the edge of the race t' .

The arrangement of the mechanism serving to impart motion to the bar m^2 by the bar x' may be varied in a similar manner as has been stated with regard to the analogous mechanism of the composer.

During the upward motion of the bar x' , produced by the spring z^2 , the bar m^2 is first drawn backward by the amount of its second forward motion. This may be effected by the spring o^2 attached to m^2 . The projection a^2 on the bar x' thereupon striking against the projection z' of the bar w' , the latter is forced to follow the bar x' , and the ejector u^2 is withdrawn from the race t' . While receding the ejector is, however, prevented by the foot c^3 of the holding-down bar w' from drawing along with it the following type, in case the same should adhere to the ejector. The said holding-down bar w' may also be combined with the composer B, instead of making use of the bar k , Fig. 1. The bars x' and u' going back farther, the pin d^2 , fixed in the bar u' , lifts the bar w' when it arrives at the upper end of the slit c^2 , or by striking against any shoulder of w' . The pin d^2 might also be screwed into the bar x' . Finally, the bars x' , u' , and w' complete their upward movement while the bar m^2 recedes from the channel b , so that the distributor, which up to this moment had been locked, may be shifted again.

The bar x' may be operated by hand or by a treadle in the same manner as has been mentioned to the composer.

After the types have been distributed by repetitions of the described manipulation the operator causes them to slide into the lower part of the type-channels, so that they may again be disposed of by the composer.

For the purpose of facilitating the reading of the types to be distributed it is advantageous to make the distributing-race only of such depth that the types will slightly project out of the same; but to prevent the foot c^3 of the holding-down bar w' from bearing on the types under these circumstances this bar is provided with the projections d^3 , which bear against the

top edges of the race, as has been described above.

Figs. 18 and 19 show a modification of the distributing-race. The bar m' is in this case omitted, while the fore part of the bottom of the race is made of a flat spring, a^3 , which is especially flexible at its free end, so that when the ejector presses on the front type it will bend and allow the type to pass. The other types supported by the spring descend at the same time by the amount of the curvature of the latter; but when the ejector recedes the spring, in resuming its straight form, lifts them again and recloses the aperture through which the front type had been ejected. This arrangement may also be applied to the bottom of the type-channels.

In respect to the length of the type-channels b , it is to be observed that in a working apparatus this length has to be much greater than shown in the drawings. The composing apparatus and the distributing apparatus will consequently be at such a distance from each other that the person operating the apparatus will have to stand between the two guides n and p' . Two men may consequently be engaged at the apparatus simultaneously—one for setting, the other for distributing.

By any apparatus of this kind it is possible to set and distribute types of different width or thickness, provided that their weight of body be the same. The only alteration required for types of other width consists in the substitution for the bars f and m' of other bars having notches of the proper size. The composer B or the distributor C of my apparatus may be used on another apparatus adapted for types of the same height of body. It is therefore possible to set types of different character by the same composer, it being only necessary for this purpose to take the composer from one apparatus to the other one containing the required types.

It barely requires to be mentioned that the composing apparatus may be constructed entirely separate from the distributing apparatus.

I claim as my invention—

1. The combination, with the setting mechanism or composer B, containing the ejector-bar t , with ejector l , spring u , and composing-race r , of the type-driver x and the adjuster y , co-operating with the vertical grooves m , or their specified equivalent, together with mechanism, substantially as described, for imparting the required reciprocating motion to the driver x and the adjuster y by the downward motion of the bar t , as and for the purpose specified.

2. A type-distributing apparatus consisting, first, of a number of type-channels, b , and of a register, q' , corresponding with these channels; and, secondly, of the distributing mechanism or distributor C, guided in a suitable manner, and movable transversely to and in the rear of the channels b , this distributor

comprising the bar x' , to be depressed by hand or by the foot and drawn upward by the spring z^2 , the ejector-bar u' , having the ejector u^2 attached to it, and connected by a spring, b^2 , 5 with the bar x' , the holding-down bar w' , connected with the bar x' by a spring, c^2 , the distributing-race t' , projecting with its front end above the channels b , and the pointer s' , whose distance from the distributing-race is 10 equal to the distance between any type-channel and the corresponding point of the register q' , substantially as described.

3. The combination, with the distributing mechanism C, containing the bars x' , u' , and w' , ejector u^2 , springs z^2 , b^2 , and e^2 , and the distributing-race t' , of the bar m^2 , serving as type-driver and as adjuster, and operated by the inclined surfaces k^2 and i^2 on the bar x' , together with the lever f^2 and spring o^2 , as and 15 20 for the purpose specified.

4. The type-containing race or channel, having the front portion of its bottom formed of a spring, a^3 , in combination with the type-ejecting mechanism, substantially as hereinbefore set forth. 25

5. The combination, with the bars x' , u' , and w' and the springs b^2 and e^2 , of the projections or stops z' and a^2 on the bars w' and x' respectively, and the projection or pin d^2 , fixed to the bar x' or w' , and acting against a shoulder or 30 other suitable part of the bar w' , as and for the purpose specified.

In testimony whereof I have signed my name to this specification in the presence of two subscribing witnesses.
